(57) **CLAIM**

The ornamental design for an instrument panel, as shown and described.

DESCRIPTION

FIG. 1 is a front, bottom, right perspective view of an instrument panel showing the new design; FIG. 2 is a front, bottom, left perspective view thereof; FIG. 3 front elevation view thereof; FIG. 4 is left-side elevation view thereof; FIG. 5 is a right-side elevation view thereof; FIG. 6 is bottom plan view thereof; and, FIG. 7 is a top plan view thereof.

The broken lines of even length shown in the drawings illustrate portions of the instrument panel that form no part of the claimed design. The broken lines of uneven length illustrate the boundary of the claimed design and form no part thereof
